his Attorney

UNITED STATES PATENT OFFICE.

THEODOR BACHOFEN, OF WEST HOBOKEN, NEW JERSEY.

ROTARY CUTTER FOR PILE-FABRIC LOOMS.

Application filed June 19, 1922. Serial No. 569,480.

To all whom it may concern:

Be it known that I, THEODOR BACHOFEN, a citizen of the United States, residing in West Hoboken, in the county of Hudson and 5 State of New Jersey, have invented certain new and useful Improvements in Rotary Cutters for Pile-Fabric Looms, of which the following is a specification.

This invention relates to improvements 10 in producing cut pile fabrics of the type consisting of a base or under body having firm woven warp and weft threads superposed by a loosely twisted float filler interwoven at intervals to produce alternate bound or confined, and free or unconfined stripes, usually 15 relatively wide, the filler thread of the latter, when cut transversely, untwisting, brooming and expanding to present a soft nap or pile surface well known to the art, 20 the invention being an improvement over my former Patent Number 1,418,512.

One object of the present invention is to provide a series of rotary cutters and means 25 for driving the same whereby the float filler warp threads are severed at the centers of the slightly raised free stripes as the fabric is advanced by the action of the loom in weaving.

Another purpose is in the provision of 30 means for guarding and guiding the cutters with respect to the stripes they are operating upon, such means consisting of a metal shoe or guard in which each cutter operates and resilient washers intermediate adjacent 35 cutters.

A further aim is to produce means for mounting the guard shoes so as to be firmly supported but permitting their ready removal in small groups whenever desired 40 without interference with these remaining in operative position, said shoes being directed centrally of the stripes by their connection with the pile wires.

These and other similar aims and objects, 45 which will appear as the description proceeds, are accomplished by the novel construction, combination and arrangement of parts hereafter described and shown in the annexed drawings, forming an essential portion of this disclosure, and in which:

Figure 1 is a partial longitudinal sectional view of parts of a conventional type of loom the view being largely diagrammatic, illustrating the application of the invention.

Figure 2 is a top plan view of the front

portion of same, drawn to an enlarged scale and showing the general assembly.

Figure 3 is a transverse sectional view of the support rail, shaft and guide rod, the cutter and shoe showing in side elevation 60 and illustrating the operative position of parts in an enlarged scale.

Figure 4 is a further enlarged side elevational view of the shoe and cutter in detail. 65

Figure 5 is a side view of the preferred type of spring washer.

Figure 6 is a transverse sectional view taken on line 6—6 of Fig. 5.

Figure 7 is a side view of the rotary cutter used. 70

Figure 8 is a sectional view of the same taken on line 8—8 of Fig. 7.

Figure 9 is an enlarged transverse sectional view of the cutter, washer and shaft 75 assembly, the section being taken on line 9—9 of Fig. 3.

Figure 10 is a plan view of one of the bridges or shaft supports with bushing.

Figure 11 is a side view of the same. 80

In order to establish a clear conception of the invention, attention is first directed to Fig. 1, showing diagrammatically the main features of a loom and in which the numerals 20 and 20' designate respectively 85 portions of the constantly alternating upper and lower threads of the base fabric warp, the same passing upward from the warp beam 21 on which they are received in the loom, these binder warp threads passing 90 through the heddles of the harnesses, generally designated by the numeral 22, actuated in timed relation to produce the shed through which the shuttle 23 passes in alternate directions carrying the weft threads 25 of the 95 fabric base.

These weft threads are beat by the dents of the reed 24, as it is moved reciprocatively in timed relation to the action of the harness, advancing the fabric by a definite number of picks to the inch according to the fineness of the fabric. 100

The weft threads 25' constituting the upper layer or pile of the fabric become incorporated by interweaving at uniform spaced intervals with the binder warp, these threads being loosely twisted and while held firmly by the binder warp threads 20—20' at their intersections, are unconfined between the stripes thus formed, their looseness being 110

2
augmented by a certain definite narrowing or contraction of the fabric as it is woven.

The fabric as woven passes over the breast 26 of the loom and is wound upon a cloth 5 beam 27 driven by take-up devices producing a moderate stress in the fabric.

In order to maintain the pile stripes clear and slightly raised from the base fabric, wires 30 are woven into the fabric, one for 10 each stripe, each wire having its individual weight 31 for tensioning purposes, and pass over the rolls 32, between the harness elements 22 and reed 24, being raised and lowered by the forward harnesses 22', extending 15 at the front to guide the devices which sever the filler weft threads at the center of each stripe, these devices constituting the subject matter of the invention.

Secured on the upper surface of the breast 20 beam 26, near its ends, are brackets 35 having vertical raised ends 36 carrying opposed set screws 37 provided with lock nuts 38, the points of the screws bearing against the opposite edges of a rail 39 having a reinforcing rib 40 extending longitudinally at 25 the front.

Said rail rests in the brackets and is held by them at a height above the beam 26 to permit the passage of fabric therebetween, 30 the rail being adjustable both laterally and longitudinally of the loom.

Fastened by screws 41 to the lower side of the rail 39 is a plate 42 extending beyond the inner edge of the rail, terminating 35 in an upstanding ledge 43 continuing the full length of the plate and having a rounded top.

The upper surface of the rail 39 is recessed, as at 44, to receive relatively short 40 sections of a bar 45 held by thumb clamp screws 46 midway in the length of each section.

A plurality of brackets 48 of like thickness are formed with raised circular heads 45 49 at the inner projecting ends, these heads containing circular openings 50 receptive of concentric bushings 51 extending through on both sides.

The opposite corners of the brackets 48 50 are cut away and recessed, as at 52, said recesses neatly fitting the rounded upper edge of the ledge 43 so as to be hingedly or rockingly engaged and supported thereby, the overhanging portions of the clamp bars 45 55 binding the same loosely but securely.

These brackets 48 are also drilled to produce openings 53 to receive an alining rod 54 parallel and level with the ledge 43 and spacing sleeves 34 encircle the rod between 60 adjacent shoes and supports, the rod being prevented from moving endwise by cotter pins 33 as shown.

Mounted revolvably in the bushings 51 is a shaft 55 having a key-way 56, said shaft 65 having at one end a driving pulley 57 or

other means by which rotary motion from any convenient source may be communicated.

The other end of the shaft may be screw-threaded as at 58, and fitted with nuts 59 70 abutting a sleeve 60 in contact with the outer surface of the adjacent bracket 48, the opposite end bracket being in contact with a collar 61 pinned to the shaft near the pulley 57. 75

Arranged intermediate the pairs of brackets are a plurality of thin sheet metal discs or circular cutters 62 having keen bevelled cutting edges 63 and containing axial openings 64 into which extend integral keys 65 80 suited to engage the key-way 56 in the shaft as the cutters are strung upon it.

Interjacent each pair of cutters are opposed pairs of convex spring washers 66, of lesser diameter than the discs, slit as at 67 85 to increase their resilience and having an opening 68 suited to the shaft 55, the hub portion of these washers being reversed and in contact as shown.

A shoe 70 is provided with each cutter 90 disc, the same being made of sheet metal folded into an essentially U-shape, its lower outer corner being removed and a recess 71 formed in its side walls, said corner and recess being similar to the corresponding 95 corner and recess 52 of the brackets and like said brackets suited to engage the ledge 43 to be held by the clamp bar 45.

The side walls also contain perforations 72 registering with the openings 53 of the 100 brackets and like them being receptive of the rod 54. The opposite end of the shoe is cut at an angle 73, blending into the curve 74 reaching to the lower wall of the shoe, the same extending in advance as a tip or 105 tongue 75 and containing a single perforation 76 suited to engage the pile wire 30.

At the underside of the shoe is a convex guard pocket 77 directly below the center of the cutter disc 62 and into which the 110 periphery of the cutter extends, thus assuring that any threads passing over the tongue will be severed, the movement of the cutter 62 being counterclockwise as indicated by the arrows in Figs. 3 and 5. 115

From the foregoing it may be seen that a single strand of wire only is used for each cutter, the wire being fine and smooth offering no resistance to the action of the reed; that the wire is connected to the shoe by 120 merely passing it through the opening 76 and thus is readily engaged or disengaged without difficulty or damage to it or the shoe.

The rail 39 is so mounted as to be adjustable lengthwise and also limitedly to or from the reed. In place of the usual fixed knives, which constantly become dull and impede proper cutting, rotary cutters are used presenting the best possible cutting 125 130

surface and they are positively driven at a rate commensurate with the work to be done.

It is also to be pointed out that the several cutters are in a measure self adjustable, due to the interposed resilient washers 66 and if the goods be specially fine or coarse, the washers can be readily changed to suit the conditions.

As the clamp bar sections are relatively short, a corresponding section of the cutters can be removed as a unit or one or more as may be desired. Due to the cutters nearly filling the shoes, no space at their sides is presented to receive lint, bits of thread or the like to clog their action and as the actual cutting is done at the point of intersection of the curved sides, the cutters rotating outwardly, highly effective and satisfactory results are attained.

20 It will be understood that the number of cutters used correspond to the number of stripes and that the center distances of the cutters agree with those of the stripes.

From the foregoing it will be readily seen that as the pile stripes are formed on the wires 30 and the weft beaten by the reed 24, the fabric produced will be advanced towards the breast beam, the tongues 75 entering the fabric between the pile and base portions and, as the fabric moves forward, the rotary cutters are guided directly to the center of the stripes, which are thereby cut to produce the effect desired.

Although I have described my improvements with considerable detail and with respect to certain particular forms of my invention, I do not desire to be limited to such details since many changes and modifications may well be made without departing from the spirit and scope of my invention in its broadest aspect.

Having thus described my invention, what I claim as new and desire to secure by Letters Patent, is:—

45 1. Pile cutting means for pile fabric looms, comprising a rail adjustably secured over the breast beam of the loom, brackets removably engaged with said rail, a shaft revoluble in said brackets, a plurality of rotary cutters on said shaft, a guide shoe for each cutter, said shoes being engaged by the pile wires of the loom, and means for loosely supporting said shoes.

55 2. Pile cutting means for pile fabric looms comprising a rail, brackets engaged at one end therewith, a driven shaft housed in said brackets, circular cutters thereon, shoes for each cutter, said shoes being engaged at one end with said rail, a rod passing transversely 60 through all of said brackets and shoes, spacing sleeves on said rod, a sectional clamp bar for said shoes, and means for adjusting said shoes and cutters after assemblage.

65 3. Pile cutting means for pile fabric looms comprising a rail, an upstanding horizontal

ledge on said rail, a sectional bar adjustably engaged with said rail to extend over said ledge, brackets having notched ends engaged between said ledge and rail, grouped shoes disposed between adjacent brackets, a rod 70 engaging said shoes and brackets whereby they are caused to move as a unit, a shaft in said brackets, means for rotating said shaft, rotary cutters mounted on said shaft over the center of said shoes, and spring washers interposed between adjacent cutters. 75

4. Means for slitting the raised loops of pile fabric as woven, comprising a plurality of circular cutters, a rotary shaft on which said cutters are slidably mounted, means between adjacent cutters permitting lateral adjustment, shoes for said cutters having sides reduced to clear said adjusting means, concavo-convex bottoms in said shoes into which the edges of said cutters extend, brackets for 80 said shaft, and a support common to said brackets and shoes upon which they are limitedly hingedly engaged.

5. Means for slitting the raised loops of pile fabric as woven, comprising a plurality 90 of circular cutters, a rotary shaft on which said cutters are adjustably mounted, supports for said shaft disposed at spaced intervals in its length, said supports being hingedly mounted, guide shoes for said cutters, said shoes having arcuately depressed bottoms adapted to receive the peripheries of said cutters, a rod passing through all of said shoes and supports, means on said rod adapted to maintain said shoes in uniform spaced relation, and means at the free ends of said shoes adapted to engage the wires on which the pile loops are raised. 95

6. In devices for cutting the loops of pile fabric as woven, a plurality of revoluble 105 circular cutters, U shaped guards over which said cutters are adjacently disposed, a shaft on which said cutters are laterally adjustably mounted, brackets for said shaft, the ends of said brackets and shoes being recessed to present arcuate seats, a ledge receptive of said seats, means for loosely clamping the brackets and shoes on said ledge, and means for adjusting said ledge endwise and crosswise of the loom. 110

7. In devices for cutting the loops of pile fabric as woven, a plurality of cutters, U shaped guards for said cutters, rigid spacers between said guards, resilient spacers between said cutters, wires removably engaging said guards, and supports for said cutters and guards said supports permitting a limited freedom of movement. 120

8. Means for slitting the raised loops of pile fabric as woven, comprising a plurality 125 of circular cutters, a rotary shaft on which said cutters are adjustably mounted, supports for said shaft disposed at spaced intervals in its length, said supports being hingedly mounted, guide shoes for said cut- 130

- ters, flat perforate extensions formed with
said shoes, adapted to engage with the pile
wires of a loom, and a rod passing through
all of said supports and shoes.
- 5 9. Means for slitting the raised loops of
pile fabric as woven, comprising a plurality
of circular cutters, a shaft having a key-
way, a plurality of equally spaced circular
cutters thereon, keys integral with said cut-
- ters engaging the key-way in said shaft, 10
spring washers between adjacent cutters,
hingedly mounted supports for said shaft,
and means on said shaft for pressing said
cutters toward each other.
- In witness whereof I have signed my name 15
to this application.

THEODOR BACHOFEN.
